[57] CLAIM

The ornamental design for interlocking construction toy element, as shown and described.

DESCRIPTION

FIG. 1 is a perspective view of an interlocking construction toy showing our new design;

FIG. 2 is a top plan view thereof, the bottom plan view being identical;

FIG. 3 is a side elevational view thereof;

FIG. 4 is a perspective view of a second modified embodiment of the design shown in FIGS. 1-3;

FIG. 5 is a top plan view thereof, the bottom plan view being identical;

FIG. 6 is a side elevational view thereof the side opposite being identical;

FIG. 7 is a perspective view of a third modified embodiment of the design shown in FIGS. 1-3;

FIG. 8 is a top plan view thereof, the bottom plan view being identical;

FIG. 9 is a side elevational view thereof;

FIG. 10 is a perspective view of a fourth modified embodiment of the design shown in FIGS. 1-3;

FIG. 11 is a top plan view thereof, the bottom plan view being identical; and,

FIG. 12 is a side elevational view thereof, the side opposite being identical.

*FIG. 1**FIG. 4**FIG. 2**FIG. 5**FIG. 3**FIG. 6**FIG. 7**FIG. 10**FIG. 8**FIG. 11**FIG. 9**FIG. 12*
